[57] CLAIM

The ornamental design for an automobile tire, as shown and described.

DESCRIPTION

FIG. 1 is a perspective view of an automobile tire showing my new design; it being understood that the tread pattern is repeated uniformly throughout the circumference of the tire, the opposite side being substantially the same as that shown

FIG. 2 is a front elevational view thereof;

FIG. 3 is a side elevational view thereof;

FIG. 4 is a perspective view of an automobile tire showing a second embodiment of my new design; it being understood that the tread pattern is repeated uniformly throughout the circumference of the tire, the opposite side being substantially the same as that shown

FIG. 5 is a front elevational view of FIG. 4; and

FIG. 6 is a side elevational view of FIG. 4.

FIG. 1

FIG. 2

FIG. 3

FIG. 4

FIG. 5

FIG. 6
